(57) **CLAIM**

The ornamental design for a gaming device cabinet, as shown and described herein.

DESCRIPTION

FIG. 1 is a front perspective view of the gaming device cabinet of our new design.

FIG. 2 is a front view of the gaming device cabinet of our new design.

FIG. 3 is a back view of the gaming device cabinet of our new design.

FIG. 4 is a left side view of the gaming device cabinet of our new design illustrated in FIG. 1.

FIG. 5 is a right side view of the gaming device cabinet of our new design illustrated in FIG. 1; and,

FIG. 6 is a top view of the gaming device cabinet of our new design illustrated in FIG. 1.

Those portions shown in phantom are for environmental purposes only.

1 Claim, 6 Drawing Sheets
